WILLIAM S. APPLEGET, OF CRANBERRY, NEW JERSEY.

Letters Patent No. 87,899, dated March 16, 1869.

IMPROVEMENT IN THILL-COUPINGS.

The Schedule referred to in these Letters Patent and making part of the same.

To all whom it may concern:

Be it known that I, WILLIAM S. APPLEGET, of Cranberry, in the county of Middlesex, in the State of New Jersey, have invented a new and improved Carriage and Wagon-Coupling; and I do hereby declare that the following is a full, clear, and exact description thereof, reference being had to the accompanying drawings, and to the letters of reference marked thereon, making a part of this specification, in which—

Figure 1 is a perspective view of a carriage-axle, with the shackles, or two sections of my couplings, belonging thereto, attached.

Figure 2 is a detached view of a similar section.

Figure 3 is a view of a clip, which secures the shackles to the axle.

Figure 4 is a sectional view of the journal, or that part of my coupling, which is connected with the shafts or tongue.

Figure 5 is a view of a pair of shafts, with the journals of my coupling, belonging thereto, attached.

Figure 6 is also a view of a pair of shafts, which are connected to an axle by means of my couplings.

Figure 7 is a view of the sand-guard.

Similar letters of reference indicate corresponding parts in the several figures.

This invention relates to an improvement in the mode of attaching shafts and tongues to the axles of carriages, stages, wagons, sleighs, and other vehicles.

The object of the invention is to adapt a coupling, whereby the shafts or tongue can readily be made secure, and, at the same time, adjusted or moved at pleasure, without the use of bolts or nuts.

This object is attained by applying the shackles or a part of my couplings to the axle-tree, on either side, near the hubs, and the journal, or other section, to the shafts, as in the old method, the different sections being so formed that those on the shafts can readily be fitted to those on the axle, and, at the same time, the tongue or shafts be raised or lowered at will.

To enable those skilled in the art to make and use my invention, I will proceed to describe it.

This coupling is composed of four sections, *a b c d*, which can be made of iron, or other suitable material.

The shackles, or sections, *a b*, are alike in size and construction, and are attached to an axle, *E*, and the journals, or sections, *c d*, to a tongue or a pair of shafts, as shown in fig. 5, which are also alike in make.

The axle *E* is made of wood and iron, in the ordinary way, and the shackles *a b* are secured to it, at a suitable distance from the hubs, by means of clips, in the usual way, as shown at *f* in fig. 1.

The journals *c d* are secured to the shafts by means of rivets *g*, fig. 5, said sections reaching part way up the shafts, and acting as braces in the ordinary way.

The shackles *a b* are similar, in make, to those now in use for such purposes, except they are open at one side on the top, as shown at *h* in figs. 1 and 2.

The journals *c d* are made with an arm, *i*, formed with them, somewhat like a letter **T**, as shown in fig. 4.

When desirable to adjust either tongue or shafts, they are raised sufficiently so as to allow the arm *i* of journals *c d*, as shown in fig. 4, to pass through openings *h* of shackles *a b*, (see figs. 1 and 2,) when the journals *c d* will readily fit in the shackles *a b*, as shown at *m* in fig. 6, it being impossible for them to slip out, as long as the parts remain entire, till the shafts are raised again as they were, in order to adjust them, the part, or arm, *i*, fig. 4, having to be brought to such a position as to pass through opening, *h*, fig. 2, before the shafts can be removed.

In order to keep the dirt and sand from interfering with and wearing the couplings, a guard is placed over each journal, as shown at *r*, figs. 5 and 6. This guard can be made of iron or other proper substance, and extends far enough up the shafts to be made secure by two or more rivets. When the journals *c d* enter the shackles *a b*, this guard lies close over the openings in the top of the shackles, as shown at *r* in fig. 6, thus forming a shield to the dirt and sand.

This invention is useful, for it is often necessary to change the shafts for the tongue, and *vice versa*, and, by this means, it can readily be done without a wrench or pincers, the old method of removing the bolt being often tedious and difficult, on account of the thread and nut being rusted. It is also more useful, and preferable on account of guarding against accident, as, by this means, the shafts or tongue cannot become detached as long as they remain whole, which they might otherwise do through the loss of a nut or bolt.

Having thus given a description of the operation and construction of my invention,

What I claim as new, and desire to secure by Letters Patent, is—

The sand-guard *r*, in combination with the shackles *a b* and journals *c d*, constructed, arranged, and operating as and for the purpose herein shown and described.

WM. S. APPLEGGET.
